CIGARETTE ROD CONDITION MEASURING
AND INDICATING

William C. Broekhuysen, Garden City, and James W. Warren, New York, N. Y., assignors to American Machine & Foundry Company, a corporation of New Jersey

Application August 21, 1946, Serial No. 692,062

32 Claims. (Cl. 131—21)

1

This invention relates to cigarette making machinery and, more particularly, to measuring and indicating mechanism which will automatically determine the physical uniformity of the stream or rod of cigarette tobacco formed in a cigarette machine of the continuous rod type, as shown herein.

Cigarette manufacturers have, for some time, been desirous of forming cigarettes of more uniform weight, density and draw. One of the problems in achieving this aim has been the fact that there is a certain amount of variation in the weight of cigarettes produced by a cigarette machine that, as yet, has not been entirely eliminated.

For example, if a machine is adjusted to make cigarettes having a mean weight of 27 to the ounce, the cigarettes produced will usually vary from 24 to 30 to the ounce. A cigarette weighing 30 to the ounce is ordinarily regarded as too light to be marketable. Therefore, to avoid making cigarettes which are too light, the manufacturer has to adjust the machine to produce cigarettes weighing 26 to the ounce even though this may produce a cigarette which, for the type of tobacco being used, is too heavy and does not have the same desirable drawing features as cigarettes having a mean weight of 27 to the ounce. Also, there is a certain amount of waste in making over-filled cigarettes which is not to the interest of either the public or the cigarette manufacturer.

Although the present invention does not eliminate entirely the weight variation mentioned, it has for one of its objects to provide a novel device and method whereby the variation can be decreased to the extent that most of the undesirable consequences, heretofore resulting from the variations, have been either eliminated or materially reduced.

Another object is to provide strain gage mechanism to register the amount of strain exerted against the different parts of the rod forming mechanism so that an adjuster can determine quickly which part of the rod forming mechanism is not functioning properly.

Another object is to provide a device which can be used to test improvements in the tongue and guide liner construction and design to ascertain how satisfactorily they compress moving streams of tobacco.

A further object of this invention is to provide detecting mechanism which, by measuring the force exerted on the compressing device, ascertains any change that takes place in a tobacco

2

stream that is being compressed and formed into a cigarette rod.

Another object is to provide strain gage mechanism which will register the vertical, lateral and longitudinal pressures exerted against the rod forming mechanism of a cigarette machine.

Another object is to provide strain gage mechanism to measure the lateral pressure of tobacco against the sides of the channel before the entry of the tobacco stream under the rod forming tongue.

A further object is to provide strain gage mechanism which will register the vertical pressure of the tobacco rod at the tip of the tongue, at which point the tobacco rod undergoes its maximum compression.

Another object is to provide a series of strain gages, interposed along the stream of cigarette tobacco from the point at which compression is begun to the point of maximum compression, which will provide a series of measurements showing how the various compressing elements are acting on the rod throughout its length.

A further object is to provide a strain gage mechanism which will control the operation of a cigarette ejector to remove defective cigarettes having plugs and holes, or cigarettes which are extremely light or heavy.

A further object is to provide strain gage mechanism, associated with the rod forming mechanism of a cigarette machine, to regulate the rate at which tobacco is fed to the rod forming mechanism of the cigarette machine.

Another object is to provide a method of manufacturing cigarettes which will result in the production of cigarettes of more uniform density.

Other objects and features of the invention will appear as the description of the particular physical embodiment selected to illustrate the invention progresses. In the accompanying drawings which form a part of this specification, like characters of reference have been applied to corresponding parts throughout the several views which make up the drawings.

Figure 1 is a schematic front elevation of a cigarette machine showing the rod forming tongue and strain gages mounted thereon.

Figure 2 is a schematic plan view of the cigarette machine showing the rod forming tongue and strain gages mounted thereon.

Figure 2A is a cross-sectional view taken on line 2A—2A of Figure 1.

Figure 3 is an enlarged (partial) front elevation of the rod forming tongue with a portion 55 of the strain gage cover plate broken away to

illustrate the mounting for one of the strain gages.

Figure 4 is a sectional end elevation taken on the line 4—4 of Figure 3.

Figure 5 is a sectional end elevation taken on the line 5—5 of Figure 3.

Figure 6 is a sectional end elevation taken on the line 6—6 of Figure 3 showing the metal plate supporting the strain gage.

Figure 7 is a sectional end elevation taken on the line 7—7 of Figure 3.

Figure 8 is a sectional end elevation taken on the line 8—8 of Figure 3.

Figure 9 constitutes a conventional Wheatstone bridge circuit.

Figure 10 shows a suitable circuit for amplifying and detecting a change in balance in a Wheatstone bridge circuit.

Figure 11 illustrates suitable apparatus for controlling the rate of feed of a cigarette making machine by the output of a Wheatstone bridge.

Figure 12 is a partial end elevation of the cigarette machine illustrating suitable mechanism for ejecting cigarettes.

Figure 13 is an enlarged view of the magnetic strain gage.

Referring to Figures 1 and 2 of the drawings, tobacco S is showered into a chute (not shown) onto a traveling conveyor belt 1 in a manner similar to that shown in U. S. Patent No. 2,283,394 dated May 19, 1942 issued to Mr. E. D. Smith. The traveling belt 1 travels in the direction indicated by the arrow over idler rollers 2 and 3. The showered tobacco T, carried by the conveyor belt 1, is forwarded and compressed between the stationary tobacco guide liners 4 and 5 and the short conveyor belt 6. The short conveyor belt 6 travels in the direction indicated by the arrow over drive pulley 7 and take-up roller 8 and then over idler rollers 9, 10, 11, and 12. The drive pulley 7 is driven by suitable means (not shown) from the main drive of the cigarette machine. A short belt guide 13 acts to hold the belt free from lateral movement.

The tobacco guide liners 4 and 5 are fixedly connected by means of suitable clamp screws 14, 15, and 16 to tobacco guide supports 17 and 18 respectively. The rear tobacco guide support 17 is secured to the frame F of the machine by suitable means, such as clamp bolt 21. The front tobacco guide support 18 is removably secured to the frame F of the machine by means of locking clamps 19 and 20 engaging with suitable slots of studs 19a and 20a respectively, projecting from said frame portion of the machine.

After the tobacco stream T has been forwarded by the conveyor belt 1 to a position adjoining idler roller 3, it is deposited onto a continuous traveling cigarette paper tape P, where it undergoes further compression between the short conveyor belt 6, paper P and the ends 32 and 33 of tobacco guide liners 4 and 5. The paper tape P travels in the direction indicated by the arrow and is forwarded over guide roller 25 onto the folder belt 26. The folder belt 26, which supports and forwards the tobacco carrying paper tape P through the cigarette machine, is driven by drive wheel 27. The drive wheel 27 is driven in the direction indicated by the arrow by suitable means from the main shaft (not shown) of the cigarette machine. The folder belt 26 travels over idler rollers 28, 29, and 30. A conventional spring actuated take-up roller 31 is provided to hold the folder belt 26 under the de-

sired amount of tension. The entire folding unit described above is supported on the bed 22 of the cigarette making machine.

The tobacco guide liners 4 and 5 are resiliently constructed so that the distance between the converging ends 32 and 33 can be adjusted. The end 33 of the guide liner 5 is adjusted by means of an adjusting screw 34 which is threaded through the front tobacco guide support 18. A locking nut 35 is provided for locking the adjusting screw 34 in place once the adjustment has been made. The end 32 of tobacco guide liner 4 can be adjusted by means of the cone-shaped plunger 36 which is slidably mounted in boss 37. An adjusting screw 38, having a cone-shaped tip 39, is threaded through the frame F of the cigarette machine and is slidably supported in the boss 40.

By turning the adjusting screw 38, the cone 20 39 slidably engaging with the cone-shaped plunger 36, will cause the cone-shaped plunger 36 to slide longitudinally in its mounting 37 to apply more or less pressure on the tobacco guide liner 32. Since the ends 32 and 33 of the tobacco guide liners 4 and 5 are resilient, they apply an outward thrust on the cone-shaped plunger 36 and the adjusting screw 34. The adjusting screw 38 is locked in position by means of lock nut 41.

The tobacco guide liners 32 and 33 have arms 42 and 43 formed thereon which project laterally and outwardly from each of the tobacco guide liners 32 and 33. Flexible strain gage supports 44 and 45 are connected at one end to each of the projecting arms 42 and 43 by means of screws 46 and 47. The strain gage support consists of suitable material having a relatively low modulus of elasticity, a relatively high elastic limit and a high tensile strength. Examples of material suitable for this purpose are Phosphor bronze, spring brass and beryllium copper. The opposite end of each of the flexible strain gage supports 44 and 45 is connected to the rear tobacco guide support 17 and the front tobacco guide support 18 respectively.

An active and a dummy wire resistance type strain gage 44a, 44b, 45a, and 45b, of the type shown in U. S. Patent No. 2,292,549 dated August 11, 1942 issued to Mr. E. E. Simmons, Jr., are mounted on each of the supports 44 and 45. The active and dummy gages form the adjoining arms G1 and G2 of a conventional Wheatstone bridge such as shown in Figure 9.

The Wheatstone bridge shown in Figure 9 is of conventional design wherein the two resistance arms identified by the symbols R6 and R7 are equal and fixed and the two arms identified by the symbols G1 and G2 are the strain gage resistances placed in the bridge. Since the resistance of the strain gages are the same, the bridge will be in balance when no strain is exerted on the strain gage filaments G1 and G2. A source of alternating voltage is applied to the terminals marked B and D. When the cigarette making machine is in operation the resistance of strain gage filaments G1 and G2 will vary rapidly in accordance with the strain exerted by the traveling stream of cigarette tobacco. The output terminals A and C of a Wheatstone bridge can be connected after suitable amplification to the Recording Oscillograph "RU". Since the various strain gages mentioned in this application are connected in a similar manner, reference will be made for purposes of simplicity to this Figure 9 in all cases to describe how these

various connections in a Wheatstone bridge are made in each instance.

The active gage 44a is mounted on support 44 so that the axis of the filament wires, making up the gage, lies parallel to the direction in which force is exerted on the support 44. The dummy gage 44b, on the other hand, is mounted so that the axis of the filament wires comprising the gage is transverse to the direction in which force is applied to the support 44. The dummy gage 44b will, therefore, not be affected by any force exerted on the support 44 but will reflect temperature changes that occur in the support in the same manner as active gage 44a. This feature provides for an accurate functioning of the measuring device disclosed because both gages form the adjoining arms G1 and G2 of the Wheatstone bridge, and a change in temperature will affect both gages equally and consequently temperature changes will not affect the functioning of the Wheatstone bridge. The other support 45 also has an active and dummy resistance wire strain gage similarly mounted thereon which is connected to a Wheatstone bridge in a similar manner.

It will be noted that the amount of outward or lateral force exerted by the tobacco T traveling between the ends 32 and 33 of the tobacco guide liners 4 and 5 will be registered by means of the active strain gages 44a and 45a mounted on the strain gage supports 44 and 45 (Fig. 2). Suitable covers 48 and 49 are provided over each of the strain gage mountings. Three conventional wire connecting lugs are attached to each cover 48 and 49.

Inasmuch as the active and dummy gages 44a and 44b mounted on support 44, form the adjoining arms of a Wheatstone bridge, the end of one wire from each of these gages are joined together at the connecting lug 111 which corresponds to the position B of a Wheatstone bridge such as shown in Figure 9. The end of the other wire from each of these gages is connected to lugs 110 and 112 respectively which corresponds to the positions C and A of a Wheatstone bridge such as shown in Figure 9. The active and dummy gages 45a and 45b, mounted on support 45, also form the adjoining arms G1 and G2 (Fig. 9) of a Wheatstone bridge. One end of the wires from each of these gages are, therefore, joined together at connecting lug 114 which corresponds to the position marked B of a Wheatstone bridge such as shown in Figure 9. The other end of the wire from each of these gages is connected to lugs 113 and 115 respectively, which corresponds to the positions C and A of a Wheatstone bridge. Suitable wires 110a to 115a lead from each of the connecting lugs 110 to 115 to a Recording Unit shown in Figure 1.

Wires 110a, 111a, and 112a from strain gages 44a and 44b are connected respectively to wires 150, 152, and 154 shown in Figure 10. When strain gages 45a and 45b are connected to the Recording Unit, wires 113a, 114a, and 115a would be connected respectively to wires 150, 152, and 154 (Fig. 10). The wires from strain gages shown in Figures 1, 2, and 3 are similarly connected to the circuit diagram shown in Figure 10.

After the tobacco has passed between the ends 32 and 33 of the tobacco guide liners 4 and 5, it passes under a tongue 60 which compacts the tobacco in the usual manner. The tongue 60 is provided with four vertically extending lugs 61, 62, 63, and 64 (Figure 3). A strain gage support 65, made of a material similar to that of supports

44 and 45, is secured at one end to lug 62 by means of screw 66 and, at the other end, is secured to tongue support 69 by means of screw 70.

Another strain gage support 67 (Fig. 3), also made of material similar to that of supports 44 and 45, is secured at one end to lug 63 by means of screw 68; and the other end is secured to tongue support 69 by means of screw 71. It will be noted that a portion of Figure 3 has been broken away to illustrate how the gage support 67 is mounted. Each of the strain gage supports 65 and 67 has a suitable cover 72 and 73 (see Figs. 1 and 3).

Suitable resistance wire type strain gages 116 and 116a (Fig. 3), such as shown in U. S. Patent No. 2,292,549 dated August 11, 1942 issued to Mr. E. E. Simmons, Jr., are mounted on each of the supports 65 and 67. Any longitudinal pressure exerted against the tongue 60 by the tobacco T passing thereunder will be transmitted to the strain gage supports 65 and 67. The strain gages 116 and 116a, mounted on the supports 65 and 67, will register the amount of strain exerted on the supports 65 and 67. It will be noted that the supports 65 and 67 do not interfere in any material degree with the vertical movement of the tongue 60 which is measured by other means hereinafter described.

The strain gages 116 and 116a are mounted on their respective supports so that the axis of the filament wires, making up these gages, lies parallel to the direction in which force is applied to the supports 65 and 67. Inasmuch as any longitudinal strain exerted on the tongue 60 by the tobacco passing thereunder will result in equal and opposite forces being applied to the gage supports 65 and 67 because of the manner in which they are mounted, it is not necessary to mount any dummy gages on these supports. In this connection it will be noted that movement of the tobacco T under the tongue 60 will result in longitudinal pressures being exerted against the tongue 60. These pressures will be reflected in a shortening of strain gage support 67 and a stretching strain being exerted on strain gage support 65. Member 69 is held in fixed position in relation to the frame of the machine by means of the clamping screw 103. Instead of using dummy gages, gages 116 and 116a can be connected as adjacent arms G1 and G2 in a Wheatstone bridge circuit such as that shown in Figure 9.

Since both gages 116 and 116a are associated with the tongue 60, temperature changes in the tongue will affect both gages in a similar manner. Consequently temperature changes will not affect the changes in resistance shown by the Wheatstone bridge because both gages 116 and 116a form the adjacent arms G1 and G2 of the Wheatstone bridge (Fig. 9). Since the forces exerted on the strain gages 116 and 116a will be equal and opposite, the changes in resistance of gages G1 and G2 will be additive.

Cover 73 has three conventional wire connecting lugs 117, 118, and 119 formed thereon. One end of the wire from each of the active gages 116 and 116a are joined together at connecting lug 118 which corresponds to position B of a conventional Wheatstone bridge such as shown in Figure 9. The other end of the wire 117a from strain gage 116a is connected to connecting lug 117, while the other wire 119a from gage 116 is connected to lug 119. The wires 117a, 118a, and 119a lead from the lugs 117, 118, and 119 to the Recording Unit shown in Figure 1.

A bracket 74 is fixedly mounted on the vertically extending lug 61 by means of a clamp screw 75. A flexible vertical supporting plate 76 is connected at one end to the bracket 74 by means of screws 77 and, at the other end, is connected to the tongue support 69 by means of screws 78. The opposite end of the tongue 60 also has a bracket 79 which is mounted on vertically extending lug 64 by means of screw 80. A flexible vertical supporting plate 81, made of material of the same type as that used in supports 44 and 45, is connected at one end to bracket 79 by means of screws 82 and, at the other end, is connected to the tongue support 69 by means of screws 83.

The flexible supporting plate 81 has mounted on its face an active and a dummy wire strain gage 84 and 85 (see Figs. 3 and 6) which may be of the type shown in U. S. Patent No. 2,292,549 referred to above. The flexible supporting plates 76 and 81, while they support the tongue substantially free from vertical movement, do not materially restrain the tongue from longitudinal movement. The active strain gage 84 mounted on the flexible supporting plate 81, therefore, is provided for measuring the vertical strain placed on the tongue at this point by the stream of tobacco thereunder.

The active gage 84 is so mounted that the longitudinal axis of the filament wires making up the gage are positioned in a direction which is parallel to the direction in which force is applied by the tongue 60 to the supporting plate 81. The dummy gage 85, on the other hand, is mounted so that the longitudinal axis of the filament wires will be transverse to the direction of the lines of force applied to the supporting plate 81. The dummy gage 85 will register the same variations in temperature of the support 81 as the active gage 84, but changes in stress on support 81 will not affect gage 85.

The active and dummy strain gages 84 and 85 form the adjoining arms G1 and G2 of a conventional Wheatstone bridge such as that shown in Figure 9. One end of the wire from each of the strain gages 84 and 85 is joined together as shown in Figure 6 as wire 121a. Suitable wires designated as 120a, 121a, and 122a are provided for connecting strain gages 84 and 85 to the Recording Unit referred to herein. It will be appreciated that in practice it may be desirable to provide a suitable wire junction box, such as cover 72, wherein sturdy lugs are provided to support said wires 120a, 121a, and 122a, but for purposes of illustrating the invention, this has not been shown in this manner because the invention can be better illustrated by connecting wires 120a, 121a, and 122a directly to the Recording Unit as shown in Figure 1.

While it is not necessary to construct the tongue supporting structure similar to that shown herein to practice the invention disclosed, it should be remembered that the natural frequency of vibration of the rod forming mechanism, such as a tongue, should not be permitted to interfere or superimpose itself on the recordings of the strain gage. The support for the rod forming member should also be such that it will not cause the natural frequency of vibration of the rod forming member in any direction to be so low that it interferes with or detrimentally affects the formation of a cigarette rod. As is well known, the frequency of vibration of a member may be controlled by its weight, thickness, design and the physical properties of the

material it is made of and the resiliency of its support.

A reluctance type magnetic gage 90 is fixedly mounted on the vertically extending lug 64 by means of a bracket 91 and screw 92 and consists of a conventional soft iron core having wire coiled around the core and pole piece located directly above the tip of the tongue and separated from it by a narrow air gap 93. Any change in the air gap 93 between the magnetic gage 90 and the tip of the tongue, the tongue being made of magnetically permeable material, will change the inductance of the coil. If the pressure at the tip of the tongue 94 varies or remains constant, the magnetic gage will record the variation or the steady state of pressure.

The wires 123 and 124 lead from the magnetic gage 90 and are connected to contacts A and B shown in Fig. 10. A gage of substantially the same impedance and power factor as the magnetic strain gage 90 in this case is connected to contacts B and C in Fig. 10.

The tongue support 69 (Fig. 2) has three laterally extending lugs 95, 96, and 97. In each of the lugs is mounted a suitable adjusting screw 98, 99, and 100 having suitable lock nuts for holding them in position after having been adjusted. The adjusting screws 98, 99, and 100 engage with a fixed stationary portion of the cigarette machine frame and, when adjusted, properly positions the tongue above the paper tape P and folder belt tape 26. A clamp arm 101, pivotally mounted to the frame of the cigarette machine by means of pivot screw 102, carries a clamp screw 103 for holding the adjusting screws 98, 99, and 100 and the tongue support down over the bed of the cigarette machine.

After the continuous cigarette rod emerges from the tip of the tongue 94, it enters into a pasting section block where a conventional paste wheel 104 applies paste to the overlap edge of the paper tape P. The paste wheel, which is operated by suitable means from the main drive of a cigarette machine, rotates and applies paste to the overlap edge of the paper tape. The paste applying device may be similar to that shown in U. S. Patent No. 2,351,565 issued to Mr. J. W. Warren on June 13, 1944. From there, the cigarette rod C, having had paste applied to the edge of the paper tape, passes beneath suitable sealing and cutting mechanism (not shown) which cuts the rod into cigarettes of desired lengths. If desired, reference may be made to U. S. Patent No. 2,357,801 issued to Mr. C. Arelt on September 12, 1944 and U. S. Patent No. 1,883,774 issued to Mr. R. E. Rundell on November 22, 1932 for a further showing and description of these parts.

Each of the resistance wire type strain gages is cemented to its respective mounting by a suitable bonding agent. As mentioned herein, U. S. Patent No. 2,292,549 may be referred to for a more detailed description of the construction and operation of a resistance wire type strain gage.

When tobacco has been deposited on the conveyor belt 1, it undergoes a gradual preliminary compression as it passes between belts 1 and 6 and then undergoes a further compression between the paper P carried by folder belt 26 and the short conveyor belt 6. The tobacco guide liners 4 and 5 also cause the tobacco to be confined laterally. As the tobacco undergoes such compression, it will exert varying degrees of outward pressure on the ends 32 and 33 of the to-

bacco guide liners 4 and 5. The strain gage supports 44 and 45, having strain gages 44a, 44b, 45a, and 45b mounted thereon, are connected to the tobacco guide liners in the manner hereinbefore described and register the amount of lateral force of the continuous traveling tobacco stream against the ends 32 and 33 of the guide liners 4 and 5. The strain gages connected to the tongue are arranged so that they will register vertical forces as well as longitudinal forces exerted on the tongue 60 by the tobacco stream as it passes beneath and is compressed by the tongue. The term "register" is used herein and in the appended claims is intended to be synonymous in meaning and scope with the word "indicate" and is intended to include within its definition the word "recording."

The wires from the various strain gages marked 110a, 111a, 112a, 113a, 114a, 115a, 117a, 118a, 119a, 120a, 121a, 122a, 123, and 124 lead to conventional recording apparatus such as a recording oscillograph, designated by the box marked "Recording Unit." If desired, one of several commercial "Recording Units," such as that produced by Baldwin Southwark and known as the SR-4 Strain Recorder or that produced by General Electric and known as Type PM-12A oscillograph, can be used for observing or recording the forces exerted on the strain gages described herein. The Recording Unit receives current through wires 125 and 126 from a suitable source of supply and supplies current to the various strain gages which are connected to the Recording Unit.

The variation in electrical resistance of the strain sensitive filament making up the strain gage may be determined by a usual Wheatstone bridge circuit such as shown in Figure 9, in which the active strain gage filament constitutes one arm as previously mentioned.

Since a cigarette machine usually operates at a rather high rate of speed, a conventional strip or chart form of recorder is used in place of the usual galvanometer of a Wheatstone bridge. Where a continuing record is not required, a visible indicating device, such as an oscillograph, can be used in place of the usual galvanometer of a Wheatstone bridge. The chart form of recorder has the advantage of showing not only the present performance of the machine but also the past performance. This enables a trend to feed too little or too much tobacco to be readily detected and appropriate adjustments in the rod forming mechanism may be made immediately to facilitate the formation of a cigarette rod of uniform density.

Where a particular part of the rod forming mechanism, as for example the tip of the tongue, is not operating properly, the strain gage will show large fluctuations in the amount of pressure being applied to the rod. The adjuster, therefore, will not have to guess or resort to the trial and error method in order to ascertain which part of the rod forming mechanism is causing the formation of defective cigarettes; and he can go immediately to the source of trouble to remedy the defect in a minimum of time.

The invention is also exceptionally valuable for testing and comparing the performance of various designs of rod forming mechanism, such as a tongue, on different types of tobacco.

The measuring and indicating mechanism shown and described above can also be advantageously employed to operate an ejecting mecha-

nism for defective cigarettes, such as that shown in U. S. Patent No. 2,357,801 issued to Mr. C. Arelt on September 12, 1944. In such a case, the variations in pressure exerted against the rod forming member, such as the tongue 60, by defective cigarettes having holes, plugs, or being extra light or heavy, would cause variations in the resistance of the strain gate which coacts with the rod forming mechanism. The strain gage would be part of a Wheatstone bridge circuit such as shown in Figure 10 and changes in the resistance of the strain gage would change the balance of the Wheatstone bridge. Suitable means such as that shown in Figure 10 may be employed to amplify and detect this change of balance and made to operate a relay 225 in a manner broadly similar to that shown in Figure 12 and in U. S. Patent No. 2,357,801.

With reference to Figure 12 the ejecting mechanism is actuated by means of the relay 225 which corresponds with the relay 225 disclosed in Letters Patent 2,357,801. Said relay, when energized effects the setting and operation of a timing disc and indexing mechanism mounted in a housing 189. Said mechanism performs the same function and is of the same construction as the one disclosed in the above mentioned patent and is driven in synchronism with all other units of the cigarette machine by means of a shaft 182. The indexing mechanism, through a chain 184 drives a sprocket 186 which is loosely mounted on a shaft 188 and to which is attached a gear 190 driving a gear 192. The gear 192 is mounted on a shaft 194 supported by an arm 196 which is pivotally attached to shaft 188 supported in a bearing bracket 198. The latter is secured to the main frame of the machine. The free end of shaft 194 carries a pair of ejector rods 200 which, when shaft 194 is driven, rotates in the direction of the arrows shown in Figure 12. Arm 196 by means of a connecting rod 202 is connected to and oscillated by a suitable cam lever (not shown) which forms part of the indexing mechanism mentioned above. The individual cigarettes cut off from the continuous cigarette rod C emerge from a suitable cut-off (not shown) and are delivered and pushed through a guide channel 204 onto a continuously driven collector belt 206. The guide channel 204 is held by a bracket 208 adjustably attached to a lug 210 fastened to the frame of the cigarette machine.

The machine is so timed and synchronized that the rotating ejector rods 200 are lowered by connecting rod 202 and arm 196 into position to sweep off the cigarettes delivered at that moment from the guide channel 204 onto the collector belt 206. The cigarette to be ejected is caught by the ejector rods 200 in midair and thrown into an ejector chute formed by a pair of guide plates 212 and 214 which are adjustably attached to the bearing bracket 198.

In Figure 10 the external arms of the bridge G1 and G2 constitute the active and dummy strain gages referred to hereinbefore while the internal arms of the bridge consists of R6 and R7. A 5,000 cycle excitation supplied by a voltage stabilized oscillator is applied across the diagonal corners B and D of the bridge. D' is an electrical terminal corresponding to D; D' being internal and D being external. The differential output of the bridge circuit appears across the diagonal A to C and is applied through a step-up transformer T1 and an attenuator to the four-stage amplifier and demodulator, where it is amplified, rectified and filtered. The output of this unit is

a D. C. current which varies in magnitude in accordance with the ratio of resistance of G1 and G2.

To balance an A. C. bridge, it is necessary to balance its arms both in phase and in amplitude. Potentiometers R2 and R6 act as fine and coarse adjustments of the amplitude balance. Resistors R3 and R5 are added to the circuit to define and limit the range over which the potentiometers R2 and R6 can operate. Potentiometer R1 in conjunction with condenser C1 provides for phase-balancing the bridge circuit. Shunting a known resistor R8 across arm R6 by closing switch OP, furnishes a means for calibrating the sensitivity of the bridge circuit and amplifier. The output of the demodulator operates the magnet 225 whenever the strain registered by the strain gage exceeds certain predetermined limits.

The measuring and indicating mechanism employing a strain gage, shown and described above, can likewise be employed to operate a feed control which would increase or decrease the amount of tobacco fed in accordance with changes in the density of the cigarette rod being formed. In such a case, the strain gage would be connected to a bridge circuit such as that described in the preceding paragraphs. The output of the demodulator referred to above would be connected to an indicating meter as shown in Figure 11 which, in turn, would be used to actuate a control device in a manner broadly similar to that shown in U. S. Patent No. 1,864,728 issued to Mr. W. J. Hawkins et al. on June 28, 1932. This may be accomplished by mounting the contact arm 28a of the Hawkins patent on the shaft 24a of the indicating meter. The movement of the shaft 24a of the indicating meter controls the movement of the contact arm 28a.

The movement of contact arm 28a causes the Reeves drive control 60a, through segments 30a, to rotate in one direction or the other causing the Reeves drive 61a to increase or decrease the speed of the feeding apparatus 63a of the cigarette making machine. If desired, reference may be made to said Hawkins patent for a more detailed description of the manner in which said feed control operates.

The invention above described may be varied in constructions within the scope of the claims, for the particular device selected to illustrate the invention is but one of many possible embodiments of the same. The invention, therefore, is not to be restricted to the precise details of the structure shown and described.

What is claimed is:

1. In a cigarette making machine for forming a stream of cigarette tobacco into a cigarette rod, means for forwarding a stream of tobacco along a predetermined path, an elongated tongue for compressing the tobacco stream as it is forwarded along said predetermined path, spaced vertical and horizontal supports for providing a floating mounting for said tongue while maintaining said tongue substantially rigid, said supports including horizontal supports arranged so that one of said horizontal supports will be compressed when the other is stretched when the tongue, under the action of the cigarette rod, is moved longitudinally, electrical resistance wire type strain gages mounted on the horizontal spaced supports, a Wheatstone bridge circuit including said gages for yielding an additive output as a result of the motion of the cigarette rod under the tongue, and a device actuated by the output of said bridge.

2. In a cigarette making machine for forming

a stream of cigarette tobacco into a cigarette rod, means for forwarding a stream of tobacco along a predetermined path, an elongated tongue for compressing the tobacco stream as it is forwarded along said predetermined path, a pair of horizontally and rectilinearly arranged supports for supporting said tongue, the forward end of one of said spaced supports being fixedly connected to the frame of the cigarette making machine and with its rear end connected to the tongue, and the rear end of the other of said spaced supports being fixedly connected to the frame and with its forward end connected to the tongue in such a way that the forward movement of the tongue will simultaneously cause a stretching action on one support and a contracting action on the other support, said supports being made of a material having a relatively low modulus of elasticity, a relatively high elastic limit and a high tensile strength, an electrical resistance wire type strain gage attached to each of said supports, a Wheatstone bridge in which said strain gages form the adjacent arms of said bridge to effect an additive output from the bridge as the result of motion of the cigarette rod under the tongue, and a device actuated by the output of said bridge.

3. In a cigarette making machine for forming a stream of cigarette tobacco into a cigarette rod, means for forwarding a stream of tobacco along a predetermined path, an elongated tongue for compressing the tobacco stream as it is forwarded along said predetermined path, a pair of vertically arranged supports centered over the longitudinal axis of said tongue for suspending said tongue at a predetermined distance above said tobacco stream so as to effect a compression thereof, an electrical resistance wire type strain gage mounted on one of said supports so that the contraction and expansion of said support due to the up and down movement of said tongue will affect the resistance of said gage, a second electrical resistance wire type strain gage mounted on said supports in such a manner that temperature changes of the support will affect the resistance of said gage but the stretching and contraction of said support will not affect said latter gage, a Wheatstone bridge in which said strain gages form the adjacent arms of said bridge, and a device actuated by the output of said bridge.

4. In a cigarette making machine having means for forwarding a stream of tobacco along a predetermined path, mechanism for restricting and compacting the tobacco stream as it is forwarded along said predetermined path of travel, and a plurality of electrical strain gages connected to said mechanism and positioned in different planes extending through the axis of said stream to separately detect the longitudinal, vertical, and lateral amounts of pressure exerted by the stream of tobacco on the restricting and compacting mechanism as it passes by said restricting and compacting mechanism.

5. The method of making cigarettes of uniform density which consists in forwarding a stream of showered tobacco along a predetermined path of travel, compressing said tobacco as it is forwarded along said predetermined path of travel into a cigarette rod, translating the amount of physical compressing force exerted on the tobacco into electrical current, severing said rod into cigarette lengths and then ejecting any cigarette lengths that produce an abnormal flow of electrical current.

6. In a cigarette making machine having a frame, means for forwarding a stream of tobacco along a predetermined path, a tobacco compressing member having a mounting in said frame to maintain said member free from appreciable movement while reducing the cross sectional area of the tobacco stream as it is forwarded along said predetermined path of travel, and an electrical strain gage connected to said mounting for measuring the amount of non-appreciable movement of said member and thereby the pressure exerted by the tobacco stream on said member in being reduced in cross sectional area.

7. In a continuous rod cigarette machine, the combination with a channel along which a continuous stream of shredded cigarette tobacco is forwarded, a cigarette rod forming member associated with said channel for compacting tobacco passing along said channel, an electrical resistance wire type strain gage mounted on said cigarette rod forming member for measuring the pressure exerted by said shredded tobacco against the cigarette rod forming member as it is compacted, and means connected to said gage for indicating the amount of pressure exerted against the rod forming member.

8. In a cigarette machine having a channel along which a continuous stream of shredded cigarette tobacco is forwarded, a cigarette rod forming tongue, a member having a low modulus of elasticity for supporting said tongue, and an electrical resistance wire strain gage mechanism connected with said member for measuring the amount of strain exerted on said member by the rod forming tongue.

9. A continuous cigarette rod making machine having a tongue for compressing a continuous stream of tobacco being formed into a cigarette rod by said machine, a floating support for mounting said tongue on said machine to compress said stream of tobacco, and an electrical strain gage device secured to said floating support for indicating the pressure exerted on said tongue by the tobacco undergoing compression by the tongue.

10. A cigarette making machine, having a frame, a supporting means defining a confined path along which tobacco is forwarded in a continuous stream, tobacco compressing mechanism associated with said path for compressing tobacco as it is forwarded along said path, a strain gage support interconnecting said compressing mechanism with the frame so that forces exerted on the mechanism will be along the axis of said support, and a resistance wire type strain gage mounted on said supporting means for measuring the pressure exerted on said supporting means by said compressing mechanism as the tobacco stream undergoes compression.

11. In a cigarette making machine of the type making a continuous rod, a supporting means having a path along which a continuous stream of shredded cigarette tobacco is forwarded, a compressing member having a tapered surface coming into contact with the stream of tobacco to apply an increasing degree of compression to the tobacco stream going past said compressing member, a supporting means consisting of material having a low modulus of elasticity for supporting said compressing member, and electrical resistance wire strain gage mechanism associated with said compressing member supporting means for indicating the amount of pressure exerted on the tobacco stream by said compressing member.

12. In a continuous rod cigarette making machine, a supporting means having a path along which a continuous stream of tobacco is forwarded, a cigarette rod forming tongue positioned above said path for exerting a gradually increasing degree of compression on said tobacco stream as it is forwarded along said path, and a magnetic strain gage positioned over the tip of the rod forming tongue under which the tobacco stream undergoes its maximum compression for indicating the amount of pressure on said tip by the tobacco being compressed thereunder.

13. In a cigarette making machine for forming a continuous stream of tobacco into a continuous cigarette rod, a rod forming tongue for compressing tobacco being forwarded in a continuous stream along and under the tongue, a stationary support, members having a low modulus of elasticity interconnecting said support and said rod forming tongue, and electrical resistance wire strain gage mechanism associated with said members for indicating the amount of force exerted by said rod forming tongue on said members in compressing a stream of tobacco passing under said tongue.

14. In a machine for forming a continuous stream of tobacco into a continuous cigarette rod, a rod forming tongue for compressing tobacco being forwarded in a continuous stream along and under the tongue; a stationary support; vertically extending lugs formed on said tongue; elongated flexible members having a low modulus of elasticity connected between said support and said vertically extending lugs, said elongated members being mounted in a position parallel to the direction in which the tobacco stream travels; and electrical resistance type wire strain gages mounted on said elongated flexible members for registering the longitudinal strain exerted on said elongated flexible members by the tongue as it compresses tobacco being forwarded under said tongue.

15. In a machine for making cigarettes of the continuous rod type, a rod forming tongue for compressing tobacco being forwarded in a continuous stream along and under said tongue, a stationary support spaced vertically from said tongue, a mounting formed on said tongue, a member interconnecting said support and the mounting formed on said tongue and having a modulus of elasticity sufficient to reflect the amount of strain exerted thereon on an electrical strain gage, and an electrical resistance wire strain gage associated with said member for registering the amount of force exerted on said member by said tongue as the tongue compresses the tobacco being forwarded in a continuous stream under said tongue.

16. In a cigarette making machine of the continuous rod type having a compressing device for compacting a continuous stream of tobacco as it is fed along said compressing device, means for supporting said compressing device, said means having a modulus of elasticity sufficient to reflect on an electrical strain gage the amount of strain exerted on said means by the stream of tobacco moving along said compressing device, and an electrical resistance wire strain gage associated with said means for measuring the amount of deflection of said means by said compressing device as it compacts the continuous stream of tobacco.

17. In a cigarette making machine, a framework, a tape for supporting and forwarding a

15

stream of cigarette tobacco, a second travelling tape positioned above the first mentioned tape for limiting the vertical displacement of said tobacco stream, tobacco guide members positioned between said tapes to compress said tobacco laterally as it is forwarded between said tapes, a support extending at substantially right angles from said members and interconnected with said framework, and an electrical resistance wire type strain gage mounted on said support for indicating the amount of outward force being exerted on the tobacco guide members by the tobacco being compressed between said tobacco guide members.

18. In a cigarette making machine for forming a stream of cigarette tobacco into a cigarette rod, cigarette rod condition measuring and indicating apparatus comprising, a member for compacting tobacco as it is forwarded in a stream along a predetermined path, an electrical resistance wire strain gage, and a support connecting the electrical resistance wire strain gage to said member for measuring the longitudinal stress exerted on said member by the tobacco stream in the direction it moves.

19. In a cigarette making machine for forming a stream of cigarette tobacco into a cigarette rod, means for forwarding a stream of tobacco along a predetermined path, an elongated tongue for compressing the tobacco stream as it is forwarded along said predetermined path, a support for said tongue, and an electrical resistance wire type strain gage mechanism connected to said support to indicate the transverse force exerted on said tongue by the tobacco as it undergoes compression.

20. In a cigarette making machine for forming a stream of cigarette tobacco into a cigarette rod, means for compressing the tobacco stream to limit its cross sectional area, a strain gage support extending transversely from said means and connected to said machine, active and dummy resistance wire type strain gages mounted on said support for indicating the strain exerted thereon, means for joining the wires of said strain gages to form the adjacent arms of a Wheatstone bridge, and a recording unit connected to the output side of said Wheatstone bridge to register the amount of force to which said compressing means is subjected.

21. In a cigarette making machine, means for forming a stream of tobacco into a cigarette rod, guides coating with said means for reducing the travelling tobacco stream in cross section, a guide support extending outwardly from said guides and adapted to be connected to the frame of said cigarette making machine, and an electrical strain gage mounted on said support for indicating the amount of force normal to the axis of the tobacco stream to which said guides are subjected by the tobacco stream.

22. A cigarette machine having means for forming a stream of tobacco into a cigarette rod, means for compacting said stream in a direction transverse to that in which the tobacco stream travels, electrical resistance wire type strain gage mechanism connected at substantially right angles with said means for registering the amount of force exerted against said means by the tobacco stream, and an indicating device for indicating the forces so exerted.

23. In a cigarette making machine having means for forwarding a stream of tobacco along a predetermined path, a tongue for reducing the cross sectional area of the tobacco stream as it

16

is forwarded along said predetermined path of travel, and magnetic strain gage mechanism mounted directly above and adjacent the tip end of the tongue for registering the amount of pressure exerted against the tip of said tongue.

24. In a machine for forming cigarettes from a stream of tobacco, a substantially rigid tobacco compressor for compressing said stream of tobacco as it is forwarded along a predetermined path of travel, a member spaced a predetermined distance from said tobacco compressor to allow an air gap between said member and said compressor, and a device for indicating any change in the distance said member is spaced from said compressor.

25. In a cigarette making machine having means for forming cigarettes from a cigarette rod, means for forwarding a stream of tobacco along a predetermined path of travel, mechanism for reducing the cross sectional area of said stream as it is forwarded along said predetermined path of travel, a member supporting said mechanism, an active resistance wire type strain gage mounted on said member for recording the amount of stress exerted on said mechanism by the stream of tobacco passing past said mechanism, a dummy resistance wire type strain gage mounted on said member, means for connecting said active and dummy gages to form the adjoining arms of a Wheatstone bridge, and a recording device connected to said Wheatstone bridge to record the amount of stress exerted on said mechanism.

26. A machine for making cigarettes from a travelling stream of cigarette tobacco comprising, means for feeding cigarette tobacco to form a stream of tobacco, means for regulating the quantity of tobacco fed to form said stream, means for forwarding said stream of cigarette tobacco along a predetermined path of travel, a rod forming device for forming said stream into a tobacco filler rod as it is forwarded along said predetermined path of travel, electrical wire type strain gage mechanism associated with said rod forming device to register the amount of pressure exerted on said device by said travelling tobacco filler rod, and means interconnecting said strain gage device with said regulating means to control the quantity of tobacco fed.

27. In a machine for making a cigarette rod from a stream of tobacco, mechanism for forwarding a stream of tobacco along a predetermined path of travel, a device for reducing the cross sectional area of the tobacco stream as it is forwarded along said predetermined path of travel, and a resistance wire type strain gage associated with said device for measuring the amount of force applied at right angles to the direction of travel of said stream by said device prior to its formation into a cigarette rod.

28. In a machine for making cigarettes from a stream of tobacco, a source of supply of cigarette tobacco, means for forwarding a stream of tobacco from said source of supply along a predetermined path, means for regulating the quantity of tobacco forwarded from said source of supply, mechanism for compacting said tobacco as it is forwarded along said predetermined path of travel, an electric resistance wire strain gage device connected to said compacting mechanism for measuring the amount of force exerted by said mechanism on the tobacco being compacted, and means interconnecting the strain gage device with the regulating means to control the quantity of tobacco fed from said source of supply.

29. In a cigarette making machine for forming a stream of cigarette tobacco into a cigarette rod, cigarette rod condition measuring and indicating apparatus comprising, a member for compacting tobacco as it is forwarded in a stream along a predetermined path, and an electric resistance wire type strain gage associated with said member for indicating the force exerted transversely of the axis of the stream against said member by the stream being compressed thereby.

30. In a machine for making cigarettes from a stream of tobacco, a source of supply of cigarette tobacco, means for forwarding a stream of tobacco from said source of supply along a predetermined path, a device for compressing and forming said stream into a cigarette rod, an electric resistance wire type strain gage associated with said device for measuring the amount of force exerted by said stream against said device as it is being compressed, and means connecting said electric strain gage to cigarette ejecting mechanism for ejecting defective cigarettes detected by said electric strain gage.

31. In a machine for making cigarettes from a stream of tobacco, a source of supply of cigarette tobacco; means for forwarding a stream of tobacco from said source of supply along a predetermined path; an elongated device positioned above said path to exert a gradually increasing amount of pressure on said stream as it passes under said device; a pair of members supporting said device so that a force exerted on said device results in a force being exerted on one of said members which is equal and opposite to the force being exerted on the other of said members; resistance wire type strain gages mounted on said members; means for joining said gage together to form the adjoining arms of a Wheatstone bridge; and an indicating device associated with said Wheatstone bridge for showing the amount of pressure being exerted on said elongated device by the stream of tobacco passing thereunder.

32. In a machine for making cigarettes from a stream of tobacco, a source of supply of cigarette tobacco, means for forwarding a stream of tobacco from said source of supply along a prede-

termined path, a device for compacting said tobacco as it is forwarded along said predetermined path of travel, a strain gage support connected to said device so that the amount of pressure exerted by the tobacco against said device will be transmitted to said strain gage support, an active resistance wire type strain gage mounted on said support for measuring the amount of strain exerted on said device by the tobacco stream undergoing compression, a dummy resistance wire type strain gage mounted on said support for reflecting temperature changes in said support and a Wheatstone bridge wherein said resistance wire strain gage forms the adjoining arms thereof.
